WINDOW LOCK
Samuel Segal, Brooklyn, N. Y.
Application May 5, 1939, Serial No. 271,997
1 Claim. (Cl. 292—251)

The subject matter of this invention is a window lock of the type having a support fixedly sustained by one window frame and having means adapted to be forced against a companion window frame to prevent slideable displacement of the window frames relative to each other. The dominant object of the invention is realized in the provision of a simplified and functionally and structurally improved window lock including a support having means for slideably guiding a channelled shaped member having sides widely straddling the support which adjustably and threadably sustains a relatively elongated bolt rotatably associated with the sides of the channelled member for rectilinearly displacing the latter relative to the support to cooperate with and frictionally engage a window frame to prevent shifting thereof relative to its companion window frame. Other objects, advantages, and features 20 of the invention will be readily understood from the teachings of the following detailed disclosure considered in connection with the accompanying drawing wherein:

Fig. 1 is a perspective view of the window lock according to the invention.

Fig. 2 is a sectional view on the line 2—2 of Fig. 1 and

Fig. 3 is a sectional view on the line 3—3 of Fig. 1.

30 The window lock generally denoted 10 includes a support or block 11, a channelled member or bracket 12, and a threaded bolt 13. The block embodies laterally extending lugs 14 appropriately perforated to receive screws 14' for fixedly fastening the block to the lower slideable window frame 16.

The block is provided with a centrally arranged and longitudinally disposed groove 15 having vertical walls for slideably guiding the rectangularly shaped base 18 of the bracket 12 which includes the upstanding sides 19 and 20 widely straddling the sides of the block.

According to the invention the adjustable bolt 13 is utilized to shift the bracket in pressural relation against the companion slideable window frame 21 to prevent displacement of the latter relative to frame 16. To this end the body of the support is provided with a threaded bore 22 meshing with the threads of the shank 23 of bolt 13.

The shank is rotatably received in the opening or bearing 24 in side 20 of the bracket and is provided with the terminal manipulator or eye 25. The threaded shank has a reduced portion 26 rotatably sustained in the opening or bearing 27 in

the hub 28 struck out of the side 19 of the bracket. The reduced portion 26 together with shank 23 define the annular shoulder 29 which constitutes means for urging hub 28 in a direction away from the block when the manipulator is rotated in one direction.

It will be observed that by providing bearing 24 in the side 20 of the bracket, the latter will be continuously held in an assembled or retained relation with the block or support 11 previous to mounting the latter on a window frame. Without this retained relation of the bolt and bracket, the loose connection between shank 23 and hub 28 would allow tiltable separation of the support from the bracket or yoke.

Integral with the reduced portion 29 of the shank is the flange 30. This flange cooperates with hub 28 to shift side 19 of the bracket in a direction towards the block when the manipulator is rotated in another direction.

Where it is desired to lock or fasten frame 21 against movement in respect to the companion frame 16, manipulator 25 is rotated in one direction. It follows that shank 23 is rectilinearly displaced relative to the fixed support. Since shoulder 29 at this time abuts hub 28, side 19 of the bracket or carriage will be shifted in a direction towards the frame 21 and of course side 19 of this bracket at this time will be shifted away from the support.

Where the bolt is rotated to actuate the carriage 12, the latter will be displaced rectilinearly relative to the support by reason of the vertical guide faces of groove 15 cooperating with the sides of base 18. Continued rotation of the bolt in the same direction ultimately causes side 19 to engage the frame 21. Further rotation in the same direction sets up a frictional and pressural engagement of side 19 against frame 21 and consequently the latter is prevented from being shifted in respect to its companion frame 16.

In case it is desired to release this pressural engagement the bolt is rotated in a counter direction. In this connection flange 30 abuts hub 28 and thus drives side 19 away from the frame 21 and of course towards the support or block 11.

While the invention has been specifically described in detail, it is to be understood that it is not limited to specific details described but is capable of other adaptations and modifications within the scope of the appended claim.

I claim:

In a window lock for engaging and disengaging a window frame, a support having a centrally

arranged cut out portion disposed at the lower part thereof, a bracket comprising a base slidably guided by the walls of said cut out portion and including a pair of upstanding sides widely straddling the sides of said support, a bolt in part rotatably sustained by said sides and threadably associated with said support and having a shoulder for actuating said bracket for rectilinearly displacing one of said sides towards and against

10 said frame upon rotation of said bolt in one direc-

tion and having other means for shifting said last mentioned side from said frame upon rotation of said bolt in an opposite direction, and manipulatable means carried by said bolt and outwardly overhanging said bracket, the other side of said pair having bearing means rotatably receiving said bolt and constituting means to prevent tiltable separation of said support and bracket.
